UNITED STATES PATENT OFFICE.

ARTHUR FAGET, OF SAN FRANCISCO, CALIFORNIA.

SYSTEM OF PRECOOLING FRUIT-CARS OR THE LIKE.

941,443.

Specification of Letters Patent. Patented Nov. 30, 1909.

Application filed January 19, 1909. Serial No. 473,056.

To all whom it may concern:

Be it known that I, ARTHUR FAGET, a citizen of the United States, and resident of San Francisco, in the county of San Francisco and State of California, have invented a new and useful System of Precooling Fruit-Cars or the Like, of which the following is a specification.

My invention relates to means for establishing proper conditions of temperature in a chamber containing fresh fruit or other perishable vegetable goods. It has heretofore been proposed to establish proper temperature conditions in a railway car loaded with fruit or the like before starting it out upon its run from a packing place to a place of market, and this has actually been done by withdrawing air from one end of a car and replacing it by air at an appropriate temperature, introduced at the opposite end of the car. This system is objectionable, in that it does not replace all of the air in the car promptly, and also because the change of temperature effected is not gradual or uniform throughout the car. Perishable goods of this kind are injured by subjecting them to sudden impingement of cold air, or by subjecting different portions to unequal temperatures.

The object of my invention is to provide for a more thorough changing of the temperature of the air in the car, and to do this gradually and uniformly throughout the interior of the car, and also without subjecting any of the contents of the car to the direct impingement of cold air as it is introduced.

To these ends, my invention consists in introducing the air not only at a point or points remote from that at which the existing air in the car is withdrawn, but at widely separated points, in a stream or streams presented in a direction or directions other than toward the point of discharge, and in directions other than toward the goods contained in the car. According to one method of carrying out my invention, the air is introduced at one end of the car and discharged through suitable distributing means and removed from the opposite end of the car. According to another method, the air is introduced at an intermediate point in the car and distributed in opposite directions therefrom, while it is withdrawn at both ends of the car, but the points of discharge for the incoming air in the opposite

lead pipes, are directed away from the ends of the car toward which the leads project.

My invention will be fully understood upon reference to the accompanying drawings, in which,

Figure 1 is a schematic view, illustrating one arrangement which suggests itself for carrying out my present invention on either of the plans above outlined; Figs. 2 and 3 are, respectively, a vertical and a horizontal section through a fruit car of standard construction, in which means for carrying out one method of my invention, is embodied; Figs. 4 and 5 are, respectively, a vertical section and a horizontal section of a standard fruit car, showing a means for carrying out the other method of my invention herein disclosed; Fig. 6 is a transverse section on the line 6—6, Figs. 2 and 3; Fig. 7 is a section on the line 9—9, Figs. 4 and 5; Fig. 8 is a horizontal section on the line 8—8, Fig. 1, and Fig. 9 is a section on an enlarged scale on one of the vents shown in Figs. 2 and 3.

While not limiting myself to any particular construction of apparatus, I will proceed to describe those herein illustrated for the purpose of making known the nature of my invention.

A represents a freight car of suitable construction to receive and convey fruit or other perishable vegetable goods.

B is a pipe adapted to supply cold air from a fan C, air being led from said pipe B, through a conductor D into the hatch E of the car, or through a conductor D', through the side door F provided with an opening f. Simultaneously with the introduction of cold air from pipe B, air is withdrawn from the car through a pipe G introduced into the opposite hatch H, and for the sake of economy, the air thus withdrawn, which in the course of the process necessarily becomes mingled with some of the cool air, is passed through a pipe I and a cooling coil K, which may be of any construction, back to the fan C or other air forcing means which is to supply cold air to the car. In this manner, the entire body of air within the car may be so far changed as to establish the desired conditions of temperature therein. If the cold air is supplied through the side door F by introducing the conductor D' into the opening f, the valve d may be opened and a gate l may be swung from the full-line position to the dotted-line

position shown in Fig. 8. Under these conditions, the return pipe I will draw not only from the hatch H, but will draw through a branch pipe I' from the hatch E, and we 5 have the condition of introducing air at an intermediate point in the car and withdrawing it from both ends.

Referring now to Figs. 2, 3, 6 and 9, which illustrate a car equipment adapted for introducing air into one end of the car and withdrawing it at the other, 1 represents an air trunk line or flue extending along one side of the car beneath the roof and having a series of discharge ports 2 controlled by slide 10 valves 3 arranged along one side thereof, and a series of discharge ports 4 controlled by slide valves 5 arranged along the other side thereof. A funnel 6 communicating with the flue 1, projects through the hatch 20 H in position to make connection with whatever means may be provided for supplying cold air to the car. The slides 3 may be provided with supports 3a.

Referring to Figs. 4, 5 and 7, 7 represents 25 an air trunk line or flue adapted to be supported in an intermediate position longitudinally of a car. This trunk line or flue is provided with transverse end discharge ports 8, intermediate discharge ports 9, and 30 middle discharge ports 10, all of which are preferably arranged with their axes in the same horizontal plane, so that they discharge horizontally and not downward, and the intermediate discharge ports 9 are inclined 35 toward the middle while the ports 10 are inclined away from the middle. By this arrangement of discharge ports, the air enters the car at widely distributed points and in widely diversified directions other than 40 toward the goods within the car, and other than toward the points at which air is discharged from the car. The result of this arrangement is a thorough and uniform supply 45 of cool air to all parts of the car with a minimum discharge of the cool air before it mingles with the contained air in the car, and with a gradual reduction of the temperature uniformly throughout the car in a manner to avoid 50 deterioration of the fruit. It will be observed that the discharge ports 8, 9 and 10 decrease in diameter from the outer ends toward the middle. The trunk line or flue 7 is fed through a flue 11 at the middle, and reduction 55 of the nearest ports with a gradual increase of diameter is provided in order to render the discharge from the ports more uniform, notwithstanding their increasing distance from the supply and consequent 60 reduction in pressure.

In supplying the air at an intermediate point and withdrawing it at two end points of the car, I prefer to use an expanding chamber 12 between the inlet 13 and the supply

leg 11, and I also prefer to provide this form 65 of air supply with a false door 14 that may be fitted into the side doorway or the upper half thereof while the car is being precooled, and withdrawn before the car is shipped.

The form of apparatus shown in Figs. 2, 70 3 and 6 is intended to be a part of the permanent equipment of the car, whereas the form shown in Figs. 4, 5 and 7, especially when located in the plane in which it is illustrated, will be preferably removed from 75 the car prior to shipment. To facilitate removal, the air flue 7 is preferably constructed to be separated as indicated at 7a.

It will be understood that in the present practice of shipping fruit and like perishable goods, precooling is resorted to for the purpose of establishing proper temperature conditions before a car is started on its journey, and for the purpose of bringing the fruit to a good keeping temperature, in a 85 manner that will not deteriorate it by too sudden cooling or unequal cooling in different parts. After the car is closed up, it may, of course, be kept at proper temperature in transit by presence of ice in refrigerating compartments M supplied through 90 hatches E and H at different points *en route*.

Having thus described my invention, what I claim as new therein and desire to secure by Letters Patent is:—

1. In a precooling apparatus, the combination of the air intake pipe, the pipes extending laterally therefrom, and the series of discharge ports in the lateral pipes discharging in a horizontal plane.

2. In a precooling apparatus, the combination of the air intake pipe, the pipes extending laterally therefrom, and the series of discharge ports in the lateral pipes discharging in a horizontal plane, and constructed of 105 gradually increasing dimension.

3. In a precooling apparatus, the combination of the air intake pipe, the pipes extending laterally therefrom, and the series of discharge ports in the lateral pipes discharging in a horizontal plane, and inclined toward the middle.

4. In a precooling apparatus, the combination of the feed opening, the expanding chamber, into which the feed opening discharges the intake leading from the expanding chamber, and the discharge openings fed from the intake.

5. In a precooling apparatus, the combination of the false door adapted to fit a 120 doorway of a car or other opening, an air intake extending from said false door, and suitable discharging means supplied by said intake.

ARTHUR FAGET.

In presence of—

A. L. BABCOCK,
M. MACFERRIS.
